Specification for Design.

Patented Dec. 6, 1921.

Application filed April 2, 1921. Serial No. 458,041. Term of patent 7 years.

To all whom it may concern:

Be it known that I, PAUL MOHRMANN, a citizen of the United States, residing at Chicago, in the county of Cook and State of Illinois, have invented a new, original, and ornamental Design for a Frame for Lanterns, of which the following is a specification, reference being had to the accompanying drawing, forming a part thereof.

Figure 1 is a side elevation of a frame for lanterns, showing my new design.

Fig. 2 is a top view of one half of the frame.

I claim:

The ornamental design for a frame for lanterns, as shown.

PAUL MOHRMANN.
